ATTORNEY.

UNITED STATES PATENT OFFICE.

WILLIAM P. AIKIN, OF WATERTOWN, NEW YORK.

APPARATUS FOR DRESSING PULP-WOOD GRINDSTONES.

1,406,138.

Specification of Letters Patent.

Patented Feb. 7, 1922.

Application filed December 16, 1920. Serial No. 431,126.

To all whom it may concern:

Be it known that I, WILLIAM P. AIKIN, a citizen of the United States, residing at Watertown, in the county of Jefferson and State of New York, have invented certain new and useful Improvements in Apparatus for Dressing Pulp-Wood Grindstones, of which the following is a specification, reference being had therein to the accompanying drawings.

This invention relates to method of and apparatus for dressing pulp-wood grindstones, and has for an object to provide a dressing for a grindstone conforming substantially to the present practice, but insuring uniformity and completeness of dressing not securable by the present practice.

In accordance with the present practice of dressing pulp-wood grindstones the desideratum is a production of a reticulated surface upon the periphery of the stone, the reticulation being in the form of closely associated pyramidal teeth interspersed by leads in the form of deeper grooves, or furrows, for the purpose of conveying away the comminuted material resulting from the engagement of the pyramidal teeth with the fibres. As at present practiced, the grindstone is dressed by applying to the periphery a roller, or cylinder carrying a burr having ribs thereon, spaced in proper relation complementary to the leads which it is desired to produce in the periphery of the stone, and by continued rotation of the two parts in forced engagement excavating the grooves, or leads, to the required depth. After this a different burr is substituted having a reticulated surface complementary to the pyramidal teeth, which forms the grinding surface of the stone by a like rotation under force. It is obvious that applying the two burrs separately will result in non-uniformity, not only of the relation of the grinding teeth to the leads but the relation of the leads and grinding teeth to the cylindricity of the stone.

The present invention involves the use of a single burr having a peripheral surface complementary to the desired completed surface of the stone; that is to say, embodying ribs complementary to the leads, and striations complementary to the reticulated surface of the grinding teeth. The relation of the leads, as well as the striæ of the reticulations to the cylindricity of the stone may

be any relation required by the exigencies of use, or personal preference. For instance, the leads may be in parallelism with the axis of the stone and the striæ in parallelism and perpendicular respectively, or the leads and striæ may be spirally disposed, or the leads only may be spiral while the striæ are respectively parallel with the axis and circumferential. The present invention is not limited in any way to the relation of the several parts to the cylindricity of the stone.

In the drawings:

Figure 1 is a view somewhat diagrammatic of a fragmentary portion of a grindstone with a burr in accordance with the present invention contacting therewith in dressing relation;

Figure 2 is a view in side elevation of a burr having the lead forming ribs and the striations in parallelism with the axis, and

Figures 3 and 4 show the ribs and the striations spirally disposed, the pitch of the spiral being different in the two figures.

Fig. 5 is a fragmentary view of another form of burr.

The pulp-wood grindstone indicated as an entirety at 10 is provided with leads 11 and grinding teeth 12. The grinding teeth 12 according to the present practice are closely associated pyramids, the apexes of which conform to the periphery of the grindstone with the leads excavated to a greater distance than the striæ forming the grinding teeth. As heretofore explained, the leads 11 are under the present practice produced by a burr having ribs complementary only to these excavations, and after the leads are formed, a second burr is employed having a surface complementary to the grinding teeth.

According to the present invention a burr indicated as an entirety at 13 is employed, which may be as found desirable, a hollow cylinder or a solid roller. Irrespective of its organized formation its surface is provided with a plurality of ribs 14 which are complementary to the leads 11 formed in the grindstone and interspersed pyramids 15 formed by striations in opposite directions, either perpendicular to each other, or as the requirement of the grinding surface may make necessary, and in any case complementary to the grinding teeth 12 of the stone.

It will be at once apparent that the employment of a single burr embodying the entire complementary conformation will result

in the production of absolute uniformity of surface and therefore produce the greatest efficiency in operation by producing grinding teeth conforming accurately to the cylindricity of the stone and properly spaced relative to the leads. The burr shown at 13 is, of course, journaled upon such a device as is usually employed for the purpose of holding the burr in proper tensional engagement with the rotating grindstone, permitting the practically automatic dressing of the stone by simply applying the burr thereto with the proper tension. As at present practised, skill is required in the dressing of a stone and even in the employment of skill results are not uniform and efficiency is lowered.

What I claim to be new is:

1. An apparatus for dressing a pulp-wood 20 grindstone consisting of a burr having a striated peripheral surface with spaced ribs extending radially beyond the striated surface.
2. An apparatus for dressing pulp-wood 25 grindstones consisting of a burr having a

reticulated surface with ribs spaced upon and extending radially beyond the reticulated surface.

3. An apparatus for dressing pulp-wood grindstones consisting of a burr having 30 closely associated pyramidal grinding teeth, the apexes of which conform to a cylinder, and ribs spaced relative to the grinding teeth extending radially beyond the teeth and conforming to a cylinder of greater 35 radius than the cylinder of the teeth.

4. An apparatus for dressing pulp-wood grindstones, consisting of a cylindrical burr having a plurality of spaced reversely tapered ribs formed upon its periphery, with 40 striations intermediate the ribs forming grinding teeth, the exterior ends of which conform to a cylinder of lesser radius than the cylinder of the ribs.

In testimony whereof I hereunto affix my 45 signature in presence of two witnesses.

WILLIAM P. AIKIN.

Witnesses:

F. W. AIKIN,
GRACE L. ANDREWS.
